OBADIAH B. BROWN, OF MALDEN, MASSACHUSETTS.

Letters Patent No. 70,403, dated November 5, 1867.

CLEANER FOR LAMP-CHIMNEYS.

The Schedule referred to in these Letters Patent and making part of the same.

TO ALL WHOM IT MAY CONCERN:

Be it known that I, OBADIAH B. BROWN, of Malden, in the county of Middlesex, and State of Massachusetts, have invented a new and improved Cleaner for Lamp-Chimneys; and I do hereby declare the following to be a full and correct description of the same, reference being had to the accompanying drawings, in which—

Figure 1 is a perspective view of my improved chimney-cleaner, and

Figure 2 is a longitudinal central section, showing the mode of attaching the handle.

The same letter marks the same part in both figures.

If the fingers of the human hand were long enough for the purpose, there would perhaps be no better mode of cleaning the interior of a lamp-chimney than by wrapping a piece of suitable cloth around the finger and rubbing the interior of the chimney with it. The fingers, however, not being sufficiently long to reach all parts of the interior of the ordinary chimneys, my object in this invention is to supply a substitute that shall have the requisite length, and resemble, as nearly as possible, in its action, the pressure and movements of the natural finger. With this view, I employ a piece of rubber tube, or a solid rubber cylinder, flexible in all directions, and yet sufficiently stiff to exert a proper pressure upon the surface of the glass.

The nature of my invention, therefore, consists in the use of a flexible elastic tube or cylinder, attached to a suitable handle for the purpose of applying a cloth or other proper material to the interior of lamp-chimneys to cleanse them.

In the drawing, A marks the handle, and B the rubber tube or cylinder, attached to the handle in any convenient way.

I am aware that lamp-cleaners have before been made of rubber, and therefore I do not claim a rubber lamp-cleaner broadly; but what I claim as my invention, and desire to secure by Letters Patent, is—

A lamp-chimney cleaner, consisting of an elastic cylinder or tube attached to a handle, substantially in the manner described.

The above specification of my said invention signed and witnessed at Boston, this 24th day of April, A. D. 1867.

O. B. BROWN.
